UNITED STATES PATENT OFFICE.

LESLIE G. S. SLOCUM, OF SAN FRANCISCO, CALIFORNIA; FRANCIS J. KNAUSS, ADMINISTRATOR OF SAID LESLIE G. S. SLOCUM, DECEASED, ASSIGNOR TO THE BREWER TITCHENER CORPORATION.

AUTO TOP WINDOW FRAME.

Application filed August 7, 1918. Serial No. 248,667.

To all whom it may concern:

Be it known that I, LESLIE G. S. SLOCUM, a citizen of the United States, residing at the city and county of San Francisco and State of California, have invented new and useful Improvements in Auto Top Window Frames, of which the following is a specification.

This invention relates to a curtain window structure, and particularly to complementary separable frame sections for binding curtain lights in leather or textile fabrics such as are employed in the construction of auto tops and the like and more especially such in which a lining is used in connection with curtains of this kind.

One of the objects of the present invention is to provide a simple and substantial clamping frame for securing a plate glass window or other transparent pane therebetween, and particularly a curtain light frame adapted for use in connection with the flexible top material as used in an auto side or rear curtain.

Another object of the invention is to provide a structure whereby the following results may be obtained: first, an all metal separable frame capable of being economically made up of stampings and adapted to be wholly concealed between the curtain and lining plies in the fashion of a so-called fully blinded-in light, and in which neither mouldings, screws nor other fastening means are visible, either from the exterior or the interior of the car; second, a frame which provides a rattle-proof substantial support for the sight pane, and a secure frame attachment for the fabric forming the top; third, a neat and effective means for making a water and dust proof joint between the inner border of the curtain or curtains and the marginal edge of the pane; fourth, a frame which may be readily installed with a minimum of labor and expense; fifth, a frame which lies substantially flush with the curtain, and which eliminates recesses for the collection of dust or water either on the exterior or interior side of the top; sixth, a frame which as a whole may be supplementally supported by suitable strap members independent of the curtain to eliminate excessive sagging or straining of the fabric, and these straps are also concealed between the curtain and lining plies to further enhance the finished appearance of the frame

installation; seventh, a clamping frame by which an even tension may be applied, thereby reducing the danger of straining or breaking the glass; eighth, a frame in which the curtain and lining material is inturned and interposed between the frame sections and the pane, thereby forming a cushion for the pane, and at the same time providing effective means for securing the curtain and lining material to the respective frame sections.

Further objects will hereinafter appear.

The invention consists in certain novel arrangement or combination of curtain light elements and other constructive features, all of which are hereinafter more fully described in connection with an illustrative embodiment thereof shown in the accompanying drawings, in which:

Figure 1, is a front view of the window frame assembly showing certain parts partially broken away.

Figure 2, is an enlarged cross section on line 2—2 of Figure 1.

Figure 3, is a fragmental perspective view of one of the frame sections preparatory to the assembly thereof.

Figure 4, is a similar perspective view of the other frame section.

Referring to the drawings in detail, 1 indicates the exterior section of an auto top or curtain, and 2 the lining material employed. Adapted to be interposed between the curtain proper and the lining is a separable frame which, in this instance, consists of a pair of adjoining or contiguous sections such as represented respectively by Figures 3 and 4. These sections may be formed to provide any shape desired, and may be constructed of any suitable material, but preferably of light sheet metal or the like and it will be observed that these complementary sections are so disposed that certain parts thereof substantially lie in contact with each other. Each complementary frame section may be provided with a longitudinally disposed endless flange designated as 3 and 4 respectively, which flanges are preferably parallelly mounted or substantially so with respect to the faces of the sight pane clamped therebetween as shown in Fig. 2. The disposition of said longitudinal flanges is an important element in the structure of the respective separable frame sections and it will be observed that the innermost edge thereof is placed

in an overlapping contiguous relation along the respective marginal faces of the sight pane 14 while the outer flange margin or perimeter extends well beyond the pane margin.

For properly centering the complementary frame sections with respect to each other, said longitudinal flanges may be provided with co-operating retaining means laterally disposed from the respective flanges 3 and 4 in a substantially normal relation thereto; in the specific disclosure shown in the drawings, each of said flanges is equipped with endless flank portions designated 5 and 6 respectively, which are disposed crosswise of the plane of the pane 14, and are made to telescopically co-act for frame centering purposes. It will be seen that said laterally disposed flank reinforcements 5 and 6, impart to each of the frame sections, a rather sharply defined, angle-shaped cross-sectional profile as formed between the respective flanges and its integrally formed flank portion, and that such reinforcement serves to materially augment the lateral stiffness and rigidity of the individual endless flanges 3 and 4 of said complementary frame sections.

In order to secure the frame sections together, I preferably employ a plurality of small spaced bolts 7. These bolts may be secured in the frame flange 3, and by referring to Figs. 1 and 4, it will be seen that the complementary frame flange 4 may be perforated as at 8 to permit the bolts 7 to pass therethrough. The two frames when brought together are drawn up tight by applying nuts 9, and since the bolts are spaced at comparatively close pitch, it can readily be seen that means have been provided for applying an even tension to the frame sections when they are being drawn together. The lateral disposition of the flank members 5 and 6 relative to their respective longitudinal flanges 3 and 4 is such that when the frame sections are assembled and bolted together, they will function as a unit and the reinforcing flanks will co-act to doubly stiffen up the flanges 3 and 4 against lateral frame deflection as a whole.

It is further pointed out that in the illustrated embodiment of my invention, the pane 14 is retained against lateral displacement with respect to either frame section by the spaced clamping bolts 7 as shown in Fig. 2, which fastenings are closely disposed around the margin of the pane and made to perform double duty in that they constitute both centering and clamping means for the pane. The respective frame sections are therefore not only retained against displacement relative to each other but effective means have also been provided for holding the pane in a correlative position with respect to the assembled frame members.

In actual practice I apply the frame in the following manner: One frame comprising the longitudinal flange 3 and the flange 5 is, for instance, placed upon the curtain material or fabric such as shown at A, and the center portion of this material is then cut away to permit the inner border thereof to be inturned over the frame between the bolts 7 as shown at 10, the fabric opening being notched as at 11 to permit it to fit around the bolts and also to permit folding the inner marginal edge of the fabric over the inmost edge of said frame section. The fabric may then be temporarily secured by applying cement or the like to prevent the inturned fabric from being displaced before the frames are placed together. The complementary frame section comprising the flange 4 and the flank 6, is similarly placed on the lining fabric 2 and is secured to said frame in a similar manner as that just described. The plate glass window or pane 14 is now placed between the described complementary frame sections and may be retained against lateral displacement by means of the spaced bolts 7, which serve as a centering holding device for the same. The two fabric sections each secured to its frame section may now be brought together in such a manner that their flank reinforcements will properly register when the bolts 7 will thus pass through the perforations 8, and the nuts 9 may be applied to draw the frames tightly together against the interposed pane 14. The inner marginal edges of the curtain A which have been inturned as shown at 10, Fig. 3, and also the edges of the lining material which had been inturned over the other frame section as shown at 15, Fig. 4, are now interposed between the frame sections and the glass or pane 14, thus serving as a cushion for the glass, and they also prevent rattling of the same if the frames should accidentally loosen. The interposition of the material has further advantages, for instance, it permits greater pressure to be applied to the frames when they are drawn together, and it always permits said frames to be drawn together so tightly that a water-proof joint is formed between the fabric and the marginal edge of the pane.

It can also be seen that this clamping action serves as a means for retaining the fabric itself, thus eliminating the necessity of employing tacks or sewing the fabric to the frames, or employing other conventional fastening means for fabric securing purposes.

Another feature obtained is a smooth edge around the entire surface of each frame opening, since the inturning of the material between the frame sections as shown at 10 and 15 permits the formation of a smooth rounded fabric covered edge coming directly off the respective faces of the pane opening,

something which is certainly desirable when one considers that practically every frame heretofore employed can not be applied without cutting the material, and in such cases, always leaving a raw unfinished edge.

For the purpose of preventing sagging or stretching of the fabric composing the curtain proper and the lining, I preferably employ one or more support straps or fabric strips such as shown at 16 and 17. If desired, the inner ends of these fabric sections may be fastened between the frames when they are about to be assembled so as to be gripped by the clamped frame sections and become securely attached to the frame assembly. The opposite strap ends may then be attached respectively, the lower piece to the body of the car and the upper piece to the frame of the top which constitutes a sustaining means for said straps. The weight of the glass, together with the frame sections is thus supplementally carried by the support straps 16 and 17, and thereby preventing undue sagging or stretching of either the curtain or lining materials into which the respective frame sections are secured. A further important feature of the present invention resides in mounting said strap or straps between the plural curtains, thus making said curtain perform double duty in wholly concealing from view both the straps and the frame sections with their fastening devices.

While certain materials and a specific structure are here shown, I wish it understood that it is not my intention to limit the scope of the invention to the specific example herein illustrated, since the disposition of the parts may be varied or changed to meet various conditions in practice whenever the judgment or experience of the manufacturer may so dictate, and that various other modifications or dispositions in details of my disclosures may be resorted to without departing from the spirit and terms of my inventions as defined in the appended claims.

Having thus described my invention, what I claim and desire to secure by Letters Patent is:

1. A window frame of the character described including in combination, a two-ply curtain with an opening adapted to receive a window frame, said frame comprising a pair of endless frames, each frame having an angularly disposed flange about the outer edge thereof, and said frames adapted to telescope one within the other, a ply of the curtain being turned upon the inner face of each frame so that said frames are concealed between the plies, a pane having its marginal edge between the inturned plies of the curtain, and means for clamping the frames together.

2. A window frame of the character de-

scribed including in combination a two-ply curtain with an opening adapted to receive a window frame, said frame comprising a pair of endless frames, each frame having an angularly disposed flange about the outer edge thereof, and said frames adapted to telescope one within the other, a ply of the curtain being turned upon the inner face of each frame so that said frames are concealed between the plies, a pane having its marginal edge between the inturned plies of the curtain, a pair of supporting straps having their inner ends between the flanges of the frames, and means for clamping said frames together.

3. A window frame of the character described comprising a pair of annular metal frames, said frames being angle shaped in cross section and adapted to telescope one within the other, a pane adapted to be received between the frames, a fabric material adapted to cover each frame and also adapted to be received between the frames, means for drawing the frames together to secure the pane and the fabric material interposed between the frames, and a pair of flexible supporting members adapted to be interposed between the frames and the fabric covering the same and secured thereto when the frames are drawn together.

4. A window frame of the character described comprising a pair of annular metal frames, said frames being angle shaped in cross section and adapted to telescope one within the other, a pane adapted to be received between the frames, a fabric material adapted to cover each frame and also adapted to be received between the frames, a plurality of bolts secured to one of the frames, perforations formed in the other frame for the reception of the bolts, nuts adapted to be applied to each bolt for the purpose of drawing the frames tightly together, and a pair of auxiliary supporting members adapted to be interposed between the frames and the fabric covering the same and secured thereto when the frames are drawn together.

5. The combination with an auto curtain and the lining material therefor, of a pair of annular metal frames adapted to be secured one to the curtain section and one to the lining section, said frames being angle shaped in cross section and adapted to telescope one within the other, and said curtain section and lining section adapted to cover the frames and have their respective edges folded between the frames, a pane interposed between the inturned fabric and the frames, and means for drawing the frames tightly together.

6. The combination with an auto curtain and the lining material therefor, of a pair of annular metal frames adapted to be secured one to the curtain section and one to the lin-

ing section, said frames being angle shaped in cross section and adapted to telescope one within the other, and said curtain section and lining section adapted to cover the 5 frames and have their respective edges folded between the frames, a pane interposed between the inturned fabric and the frames, a plurality of bolts secured to one frame, perforations formed in the opposite frame 10 to permit the bolts to pass therethrough, and nuts applied to each bolt to draw the frames tightly together.

7. The combination with an auto curtain and the lining material therefor, of a pair 15 of annular metal frames adapted to be secured one to the curtain section and one to the lining section, said frames being angle shaped in cross section and adapted to telescope one within the other, and said curtain 20 section and lining section adapted to cover the frames and have their respective edges folded between the frames, a pane interposed between the inturned fabric and the frames, means to draw the frames tightly together, 25 and auxiliary members interposed between the curtain and the lining material having their inner ends secured to the metal frames and having their outer ends extended and adapted to be secured to a suitable support to 30 aid in carrying the weight of the pane and the metal frames.

8. A window installation for a curtain fabric comprising in combination a sight pane and separable continuous metallic 35 frame sections encompassing the pane and adapted to grip the pane therebetween, each of said frame sections having an endless longitudinal flange element of which the inmost edge is disposed in overlapping relation 40 along the respective faces of the pane while the perimeter thereof extends beyond the margin of the pane in spaced relation with respect to its complementary flange and each of said flanges being reinforced by laterally 45 disposed flank portions, a curtain fabric having an opening therethrough of which the inner border is interposed between the pane and the overlapping portion of one of said flanges, and screw fastenings engaging said 50 flanges, said fastenings being disposed intermediate the pane margin and the perimeter of said flange elements.

9. A window installation for a curtain fabric comprising in combination a sight pane and separable contiguous metallic frame sections encompassing the pane and adapted to grip the pane therebetween, each of said frame sections having an endless longitudinal flange element of which the inmost 55 edge is disposed in overlapping relation along the respective faces of the pane while the perimeter thereof extends beyond the margin of the pane in spaced relation with respect to said other flange and each of said 60 flanges being reinforced by laterally dis-

posed flank portions serving to maintain said flanges in a correlative position, a curtain fabric and a lining fabric, each having an opening therethrough of which the respective inner border is inturned over said inmost edge of the respective frame sections and interposed between the pane and said overlapping portions of said flanges, and screw fastenings engaging said flanges outside of the pane margin serving to bind both of the respective inturned fabrics to the pane, said frame sections and fastenings being wholly concealed between said fabrics.

10. A window installation for a curtain fabric comprising in combination a sight pane having separable contiguous metallic frame sections encompassing the pane margin and adapted to grip to pane therebetween, each of said frame sections having an endless longitudinal flange element of which the inmost edge is disposed in overlapping relation along the respective faces of the pane while the perimeter thereof extends beyond the pane margin and in which extended region said flanges are respectively reinforced by an endless flank portion to impart a substantially right angled cross-sectional shape for the respective frame sections, a curtain fabric having an opening therethrough of which the inner border is interposed between said flange elements, and means including a plurality of fastening screws to clamp the frame sections together and bind the sight pane into the fabric opening, said screws being disposed intermediate said margin of the pane and the perimeter of the respective flange elements.

11. The combination in a window installation for a curtain fabric, of a sight pane and separable contiguous metallic frame sections encompassing the pane margin and adapted to grip the pane therebetween, each such frame section being angle-shaped in cross-sectional profile comprising an endless longitudinal flange element overhanging the margin of the pane while its inmost edge is disposed in overlapping relation along one face of the pane with an endless flank portion extending laterally away therefrom, a curtain fabric having an opening therethrough of which the inner border is interposed between the pane and one of said overlapping flange edges, and clamping means adapted to draw said overhanging flange portions toward each other and serving to bind the sight pane into said fabric opening.

12. The combination in a window installation for curtain fabrics, of a common sight pane and separable contiguous metallic frame sections encompassing the pane and adapted to grip the pane therebetween, each such section being disposed in angle-shaped cross-sectional profile comprising an endless longitudinal flange element, and a flank re-

- enforcement extending laterally from an edge thereof, a curtain fabric and a lining fabric each having a window opening therethrough of which the respective inner border 5 is inturned and folded between said frame sections with the pane interposed between said inturned fabrics, and a plurality of screw fastenings serving to clamp and bind the sight pane into the fabric opening, said 10 fastenings being disposed intermediate the margin of the pane and the perimeter of the respective flange elements and wholly concealed between the aforesaid fabrics of the completed installation.
13. A window installation for curtain and lining fabrics comprising in combination a common sight pane having contiguous metallic frame sections encompassing the pane and adapted to grip the pane therebetween, 15 each of said frames having a longitudinal flange element disposed in substantially parallel relation to the pane and which flanges are respectively provided with an oppositely disposed endless flank reenforcement, a curtain fabric and a lining fabric each having an opening therethrough of which the respective inner border is inturned over the inmost edge of the respective frame sections and interposed therebetween for binding 20 purposes, and uniting means including screw fastenings serving to clamp said sections toward the pane, said uniting means causing said oppositely disposed flank reinforcements to co-act as a unit and augment the 25 rigidity of said assembled flanges against lateral deflection.
14. A window installation for curtain and lining fabrics comprising in combination a common sight pane having complementary 30 metallic frame sections encompassing the pane and adapted to grip the pane therebetween, each of said frames having a longitudinal flange element disposed in substantially parallel relation to the pane, which 35 flanges are respectively provided with an oppositely disposed endless flank reenforcement, a curtain fabric and a lining fabric each having an opening therethrough of which the respective inner border is inturned 40 over the inmost edge of the respective frame 45 sections and interposed therebetween for binding purposes, clamping means engaging said flanges for drawing the frame sections against the pane, and a support strap member secured to the clamped frame sections, 50 said strap being disposed between said linings and wholly concealed thereby. 55
15. The combination with a curtain fabric and a lining fabric, of a common sight pane therefor and separable contiguous metallic frame sections encompassing the pane and adapted to grip the pane therebetween, each such section being provided with a longitudinal flange element extending beyond the margin of the pane, which flanges are respectively provided with oppositely disposed flank portions and with means for maintaining the sections in a fixed relation with respect to each other, one of said sections being adapted to be secured to said curtain and 60 the other to said lining, the curtain fabric and the lining fabric, respectively, being adapted to be inturned and folded between said frame sections, a pane interposed between said inturned fabrics, means for maintaining the pane in a fixed relation with respect to said sections, and clamping means 65 engaging said flanges beyond the pane margin to draw the frame sections against the pane. 70
16. A window installation for a curtain fabric comprising in combination, a sight pane and separable contiguous frame sections encompassing the pane and adapted to grip the pane therebetween, each provided with endless longitudinal flange element extending beyond the margin of the pane, said flanges being respectively provided with a flank reenforcement adapted to 75 co-act and center one section with respect to the other, a curtain fabric having an opening therethrough of which the inner border portion is interposed between the pane and one of said frame sections, and screw fastening means engaging said flanges beyond the 80 pane margin to clamp the frames together and bind the pane into the fabric opening. 85

In testimony whereof I have hereunto set my hand.

LESLIE G. S. SLOCUM.

Certificate of Correction.

It is hereby certified that in Letters Patent No. 1,569,307, granted January 12, 1926, upon the application of Leslie G. S. Slocum, of San Francisco, California, for an improvement in "Auto Top Window Frames," errors appear in the printed specification requiring correction as follows: Page 4, line 68, claim 9, for the word "linging" read *lining*; line 84, claim 10, for the word "to", second occurrence, read *the*; line 114, claim 11, for the misspelled word "endles" read *endless*, and line 131, claim 12, after the word "element" strike out the comma; and that the said Letters Patent should be read with these corrections therein that the same may conform to the record of the case in the Patent Office.

Signed and sealed this 23d day of February, A. D. 1926.

[**SEAL.**]

WM. A. KINNAN,
Acting Commissioner of Patents.
